UNITED STATES PATENT OFFICE.

WILSON T. ROBBINS, OF SALT LAKE CITY, UTAH.

BOTTLE-CAPPING MACHINE.

1,355,912.

Specification of Letters Patent. Patented Oct. 19, 1920.

Application filed August 6, 1919. Serial No. 315,716.

To all whom it may concern:

Be it known that I, WILSON T. ROBBINS, a citizen of the United States, residing at 256 Reed Ave., Salt Lake City, in the county 5 of Salt Lake and State of Utah, have invented certain new and useful Improvements in Bottle-Capping Machines, of which the following is a specification, reference being had to the accompanying drawings.

10 This invention relates to an improved bottle capping machine and has for its object to provide a device of this kind including means for capping bottles of different types and sizes.

15 A further object is to provide a very simple, efficient and practical device of this kind which is capable of being cheaply made, and sold at a reasonable profit.

20 A further object of the invention is the provision of means for placing the cap on the bottle, and also means for releasing the bottle from the capper after the cap has been crimped on the bottle.

25 A further object is to provide an improved bottle capping machine, which is easy to operate and which requires a very light pressure on the operating means, such as a lever, in order to easily place the cap on the bottle.

30 The invention further aims to provide a machine which is light in weight and which is strong and durable and is so constructed as to avoid all danger of breakage.

35 While the design and construction at present illustrated and set forth is deemed preferable, it is obvious that as a result of a reduction of the invention to a more practical form for commercial purposes, the invention may be susceptible to changes, and 40 the right to these changes is claimed, provided they are comprehended within the scope of what is claimed.

The invention comprises further features and combination of parts, as will be herein- 45 after set forth, shown in the drawings and claimed.

In the drawings:

Figure 1 is a view in perspective of the improved bottle capping machine constructed in accordance with the invention;

Fig. 2 is a vertical sectional view through the same; and

Fig. 3 is a cross sectional view through the tubular member 12 at the point where the plunger stem 18 is connected to the tubular member.

Referring to the drawings, 1 designates a base, and rising upwardly from one end thereof is an upright 2, there being braces 3 between the upright and the base 1, thereby insuring rigidity between the upright and the base.

The upper sides of the upright have vertical slots 4. An elongated capper head 5, which is rectangular in cross section, is fitted between the sides of the upright, which is likewise constructed rectangular. A bolt 6 extends transversely through the head 5 and through the vertical slots 4 to hold the head in different adjusted positions on the upright. Projecting laterally from the head substantially midway its length is a boss 7 having a guide opening 8. Extending downwardly and laterally from the lower end of the head is a projection 9 terminating in a lateral part 10, provided with a guide opening 11.

A tubular member 12 is mounted in the guide openings 8 and 11, and attached to the lower end of the tubular member 12 in any suitable manner, for instance by means of threads 13, though not necessarily, is a capping cylinder 14. The interior of the lower portion of the capping cylinder is counterbored as shown thereby providing a shoulder 15 on the interior of the cylinder.

A piston 16 is guided in the counterbored portion of the lower part of the cylinder, and constitutes a bottle cap placing member, for placing the cap upon the mouth end of the bottle, which is indicated at 17. The piston or cap placing member has a plunger rod or stem 18 extending telescopically into the tubular member 12. The lower end of the plunger or stem 18 is connected in any suitable manner, preferably by threads 19, to the piston 16. The upper end of the stem or plunger has a slot 20, through which a transverse pin 21 extends. This pin is fixed transversely of the tubular member 12, by means of its head 22 and a nut 23. The plunger or stem has limited movement, owing to the opposite ends of the slot 20 contacting with the pin 21.

Mounted upon the pin 21 and arranged adjacent the stem or plunger at diametrically opposite portions thereof are spacing sleeves 24, thereby holding the stem or 5 plunger concentrically spaced within the tubular member 12. Interposed between the piston and the upper end of the capping cylinder and in surrounding relation to the stem or plunger, is a coil spring 25, acting to 10 hold the piston in its lowermost position adjacent the lower marginal edge of the capping cylinder.

One end 26 of a lever 27 is pivotally mounted at 28 to the capper head 5. The 15 upper end of the plunger is pivotally mounted between the sides of the lever 27, there being a pivot pin 30 extending through the sides and the lever 27, whereby as the lever is raised or lowered, the capping cylinder 20 and 14 is correspondingly moved.

The bottle to be capped is placed upon the base 1 and the capping head 5 is adjusted according to the height of the bottle to be capped, for it is obvious that the sleeve or 25 capping head may be adjusted in different positions for capping bottles of different heights. The bottle is arranged in position axially with the capping cylinder, and the cap to be fitted to the mouth end of the bottle is placed upon the mouth end of the bottle, and subsequently the lever 27 is lowered, in which case the cylinder is positioned adjacent the cap which is in the form of a disk. A further movement of the lever 30 causes the capping cylinder to move downwardly over the mouth end of the bottle, the cap being forced upwardly into the capping cylinder, owing to its marginal portion being bent down around the bead of the 35 mouth end of the bottle. During this operation of the capping cylinder, the piston 16 is forced upwardly until it contacts with the shoulder 15. After the cap has been crimped, the lever 27 is raised. As the capping cylinder moves upwardly the piston moves downwardly under the action of the spring 25 thereby removing the mouth end of the bottle and the cap. The bottle is removed, and another bottle is placed in position and the operations previously stated 40 are then repeated for capping the next bottle.

The opposing side faces of the capper head 5 are provided with grooves 5^a for the 45 reception of the opposite sides of the upper portion of the upright to prevent pivotal movement of the head on the pin 6. The upright 2 is constructed from a single piece of sheet metal, bent to form the double-sided 50 upper portion of the standard, and the lower parts of the sides of the upper portion of the standard diverge downwardly and are connected to the base 1. Where the diverging portions merge downwardly from 55 the opposite sides of the upper portion of

the upright a spacing block 5^b is secured by the pin 5^c, thereby holding the opposite sides of the upright rigid.

The invention having been set forth what is claimed as new and useful is:—

1. In a bottle capping machine, a frame having an upright provided with an elongated guide loop, a capping head having vertical channels on its outer side faces, in which the sides of the guide loop engage, 70 the sides of the guide loop having slots, means passing through the head and through the elongated slots for holding the sides of the loop in engagement with the channels, whereby the capping head may 80 have vertical movements, a lever pivoted on the head, a reciprocating capping cylinder, a tubular shank connected thereto and mounted in guides of the head, and in turn pivotally connected to the lever, and means 85 mounted in the capping cylinder for removing the mouth end of the bottle as the cylinder is raised.

2. In a bottle capping machine, a frame including an upright having a looped end 90 comprising parallel sides, said sides having vertical slots, a capping head having vertical parallel channels on its outer side faces receiving the sides of the loop, means extending through the head and engaging the 95 slots to hold the sides of the loop in the channels, whereby the head may be guided during its adjustment, a lever pivoted on the head, the head having guides, a capping cylinder, a connector coupling the lever and the cylinder, a spring tensioned plunger in the cylinder for removing the mouth end of the bottle when the cylinder is raised, said plunger having means guided and spaced within and loosely joined to the connector 100 for retaining the plunger in a position in the cylinder and preventing it from binding.

3. In a bottle capping machine, a frame including an upright provided with a loop having parallel sides, a capping head having opposite parallel guides operatively receiving the parallel sides, means removably engaged through the parallel sides and said head cooperatively connecting the aforesaid parts, whereby the head may be adjusted, a 110 lever operatively mounted on the head, a capping cylinder operatively mounted on the head to have relative reciprocating movements, said cylinder including a shank in guides of the head and in turn operatively connected to the lever, and means operatively mounted in the capping cylinder for relative movement with respect thereto for removing the mouth end of the bottle after the cylinder is raised.

4. In a bottle capping machine, a frame including an upright provided with parallel sides, a capping head having guide channels in its opposite sides, operatively engaging the parallel sides, thereby guiding 130

said head, means passing through the sides and through the head for holding the aforesaid parts relatively connected, whereby the head may be adjusted for capping a bottle,
5 a lever operatively connected to the head, a reciprocating capping cylinder, a shank connected thereto and operatively mounted in guides of the head and in turn opera-

tively connected to the lever, and means operatively connected to the cylinder and movable relatively thereto for removing the mouth end of the bottle as the cylinder is raised.

In testimony whereof I hereunto affix my signature.

WILSON T. ROBBINS.
